[57] **CLAIM**

The ornamental design for burial casket hardware, as shown and described.

DESCRIPTION

FIG. 1 is a perspective view of my new, original and ornamental design for burial casket hardware, the phantom line illustrating the casket being for illustrative purposes only and forming no part of the claimed design;
FIG. 2 is a front elevational view thereof;
FIG. 3 is a right side elevational view thereof;
FIG. 4 is a left side elevational view thereof;
FIG. 5 is a top plan view thereof;
FIG. 6 is a bottom plan view thereof; and,
FIG. 7 is a rear elevational view thereof.
